UNITED STATES PATENT OFFICE.

ARTHUR E. CUSTER, OF SALT LAKE CITY, UTAH.

RIFFLE-BOX.

1,224,281.

Specification of Letters Patent.

Patented May 1, 1917.

Application filed June 1, 1915. Serial No. 31,608.

To all whom it may concern:

Be it known that I, ARTHUR E. CUSTER, a citizen of the United States, residing at Salt Lake City, in the county of Salt Lake 5 and State of Utah, have invented certain new and useful Improvements in Riffle-Boxes, of which the following is a specification.

My invention relates to the saving or recovery of minerals from gravel or ore and has for its object to provide a riffle box having a detachable or false bottom made in sections, wherein are constructed novel recesses or mercury traps to retain mercury 15 which is given a special movement whereby the valuable minerals are separated from the gravel or crushed rock, and recovered.

These objects I accomplish with the process which is carried out by the device illustrated 20 in the accompanying drawings in which similar letters and numerals of reference indicate like parts throughout the several figures, and as described in the specification forming a part of this application and pointed 25 out in the appended claims.

In the drawings in which I have shown a substantial embodiment of the device by which the process is carried out, Figure 1 is a plan view of a riffle box and a portion of 30 another, with the detachable riffle boards therein with portions of said boards cut away showing the amalgamating and separating devices.

Fig. 2 is a side elevation of the same with 35 portions of the suspension means cut away, and the position of the riffle boards shown in dotted lines.

Fig. 3 is a plan view, somewhat enlarged from the other views, of one of the riffle 40 boards.

Fig. 4 is a transverse vertical section of said board on line $\alpha\alpha$ of Fig. 3.

Fig. 5 is a vertical longitudinal section of one of the mercury traps. Fig. 6 is a similar 45 view showing the relative position of the mercury and passing material at one step in the process. Fig. 7 is a similar view showing another step in advance, and Fig. 8 is still another similar view showing an 50 other advance step in the process.

In separating the valuable minerals, such as gold, platinum, silver and other metal having a specific gravity greater than the gangue with which they are associated, mercury 55 is frequently used to form an amalgam and otherwise treat such minerals, and many

forms of jigs, tables, plates, riffles, sluices, pans and other devices have been used to separate the said minerals and gangue.

This invention may be used in placer mining and in other places where the mineral bearing substance or ore must first be crushed and then the treatment applied, and while I may describe the steps and device as applied to placer mining it will be obvious 60 that it is applicable to and it is my practice to use it in concentrating mills, behind crushing rolls, and stamps.

One of the greatest difficulties to overcome in placer mining, and more especially so, 70 where the placer deposit under treatment contains fine gold, is that the riffles in use become clogged or packed with what is commonly called black sand; this black sand is usually composed of magnetite, ilmenite, and 75 garnets. This black sand soon fills the riffles and forms a blanket-like covering over the mercury and then only the coarse gold is caught which, owing to its specific gravity settles through this black sand, the fine gold, 80 however, owing to its finely divided state and the large amount of water which is used to keep the black sand from settling too dense is washed over and lost. In a great many instances riffles of a special design 85 have been constructed and tried, where the water was given a certain whirling motion or movement, so as to keep the black sand from settling, however, it was found that where this was accomplished, the fine gold 90 was also lost owing to the violent action and rapid flow of the water necessary to keep the black sands from settling.

In the treatment or process whereby I propose to use mercury as the separating 95 medium and for the medium to lift the black sands out of the riffle in a gentle manner it will be readily seen that no violent action is required and the fine gold as well as the coarse gold can be readily saved.

In the drawings, in Figs. 1 and 2, I have shown a riffle box A, suitably suspended so that a limited longitudinal motion may be imparted to it by the eccentric B. A counter spring C is used to give a quick return 105 throw to the box. I have found in practice that as the momentum of the box requires that it be short and more riffle space is required than may be supplied with one box, other riffle boxes similarly constructed and 110 operated must be used, one of which is shown at D, and placed at the tail of said

box A and into which the partially treated material is dumped.

The bottoms of said boxes A and D are provided with riffle boards E, transversely disposed therein and contiguously placed to form a continuous false bottom in each of said riffle boxes. Each of said boards E has a plurality of recesses 1 cut therein transverse as to the individual board and longitudinal as to the box A. The said recesses 1 are parallel and spaced apart and are also in two parallel rows across the said riffle box and each recess is staggered in its relation to the longitudinally adjacent one. Between the said recesses 1, the cross riffles 2 are secured to the upper face of said riffle board E. An overhanging lip 3 is secured at the upper or head end of each of said recesses 1 partially covering the head end thereof, and tail-end cross bars or riffles 4 are transversely secured on the face of said riffle board between the rows of said recesses.

The shape of recesses 1 is immaterial except at the head end where the bottom is curved or inclined upwardly as at 1' and at the tail and lower corner where a pocket o is formed preferably by cutting the end at right angles to the bottom.

The steps of my process and the operation of the device are carried out as follows:—The riffle boards E, are placed as a false and detachable bottom in the said riffle boxes A and D, the lip 5 of one extending over the joint between any contiguous board. The said riffle boxes are suspended at an incline from the head toward the tail thus giving direction to the flow as shown by the arrows a. Mercury commonly called quicksilver is supplied in said recesses 1 in an amount sufficient to cover the straight bottom of said recesses and by reason of the inclination of said boards the greater volume or quantity will normally be held in the said pockets o, as shown at q. The reciprocating motion is then imparted to the said riffle boxes A and D by the eccentrics B. The said boxes will be moved first in the direction of the arrows a, and then in the reverse direction by the more rapid motion of the spring C. The mineral bearing sand and fine gravel with enough water to move it slowly through the riffle box is then fed into said box A and allowed to flow therefrom at the lower end into and through the other boxes. The rapid or spring motion given to the boxes, which I will hereafter call, the throw motion, will cause the mercury in the recesses 1 to assume a position similar to that shown in Fig. 6. In changing from its normal position as shown in Fig. 5 to that shown in Fig. 6, all material having less specific gravity than mercury such as comminuted iron ore commonly called "black sand," gravel, fine sand, slimes and water will be carried on the surface of the mer-

cury. As the mercury is thus moved, the said sands and lighter materials will change their positions from that shown in Fig. 5 as at r, to that shown in Fig. 6 as at s and the greater portion will be moved by the water toward the tail end of the boxes. All material having a specific gravity greater than mercury, such as gold and platinum will sink through the mercury and settle at the bottom of said recesses. When the eccentrics B have made a complete rotation or movement and the said boxes A and D are again given the forward or slow movement, the mercury still having a momentum in the other direction will flow up the curved or inclined bottom 1', which flow will be stopped by the overhanging lips 3, and the material in said recesses 1 will assume the position shown in Fig. 7, wherein the mercury will bank up at the head end of said recesses and the material of less specific gravity will be moved by the flow of the water and action of the moving mercury and a portion bank up against the vertical tail ends in the pockets o. When the mercury settles or is thrown into its normal position as shown in Fig. 8, which occurs just after the second throw motion has started, the material of less specific gravity will be raised and washed over the tail end of said recesses and advanced down the riffle boxes. The gold and all heavy minerals will settle in said pockets o and leave the mercury free to be moved as before explained and to act as a carrier for the lighter material, and as a screen for all metals having a greater specific gravity than said mercury. The cross riffles 2 and 4 cause all of the mineral bearing material to pass through the said recesses.

From the description it will be seen that the riffle is self-cleaning, that is, all minerals and gangue having a less specific gravity than the mercury are displaced by the mercury, and the separation is not dependent upon any violent agitation or large volume of water flowing rapidly, but is accomplished with the gentle action of the mercury by displacement, due to the differences in specific gravity, this cleaning action being accomplished by subjecting the mercury to a movement in a novel riffle having recesses or traps, wherein the physical properties of mercury are taken advantage of and applied to accomplish this action of separating the gold or platinum from the materials in which they occur, in the free state. In this process the specific gravity and liquid properties of mercury, and the specific gravity of the metals to be recovered and that of the gangue or material in which they occur, play an important part. The specific gravity of gold, being 19, platinum 16-19, mercury 13, magnetite 5.

In the operation of the riffle the mercury owing to its specific gravity of 13, is used as

a sort of wedge or lifting means to separate the gold, etc., from the material in which it is carried by forcing its way between them, thus getting the gold, etc., under it and 5 wedging or lifting the lighter materials out of the recess, thus retaining the gold, etc., by covering it and at the same time cleaning the recess of the other and lighter minerals or gangue, and not allowing them to pack over 10 the surface of the mercury and thus destroy its action as a collector of gold, etc.

By using the mercury as described and subjected to the motion provided it is readily seen that the gold and other metals having 15 a specific gravity greater than the mercury, would be caught and held under the mercury, and so retained whether they amalgamated with it or not, as I have found the case to be with rusty or coated gold, the 20 other materials or gangue under treatment, of a lighter specific gravity, are floated and displaced with the mercury and so raised gently out of the riffle recesses or traps into the current of water used in the treatment 25 or process and so conveyed into the next recess and worked over and so on to the next until it passes into the waste or tailings dump, the gold, etc., being caught in the riffle recesses and saved, by being covered with a 30 blanket coating of mercury, or amalgamated if the conditions afforded for amalgamation are perfect, owing to the long contact obtained, or in case of rusty gold or coated gold, which will not readily amalgamate, 35 would thus be covered and held in the riffle recess with a covering or bath of mercury.

Another feature of my process, which is accomplished with the use of the device invented by me, is that when the mercury is in 40 its normal position, shown in Fig. 5, the valuable particles of mineral will fall into the recesses on the sloping bottom 1' which is not covered with mercury as indicated at t, and when the boxes are given the throw or 45 quick movement the mercury will cover the said particles t so that they are subjected to

the action of the mercury, and if small and in condition for amalgamation will be carried by the forward movement in the mercury as amalgam, while if large will be 50 completely covered and carried or rolled into the pockets o by said movement, and do not have to pass directly through the mercury. It is part of my process to use more mercury than is commonly used in order that it is at 55 all times a free moving liquid instead of a slow moving bunch of amalgam after it has commenced to act on the minerals.

Having thus described my invention I desire to secure by Letters Patent and claim:— 60

1. In a device of the class described, the combination of a riffle box; a plurality of detachable riffle boards transversely placed as a secondary bottom in said box, and each having rows of longitudinal recesses cut in 65 the face thereof, each of said recesses having a portion of its bottom inclined upwardly toward the front end and the other portion curved upwardly and having its rear end at right angles to the inclined portion of the 70 bottom, to form a right-angled pocket, each of said recesses having an overhanging lip at its head end; and means to impart a longitudinal reciprocatory movement to said box and boards. 75

2. In a device of the class described the combination of a riffle box; a plurality of detachable riffle boards each having rows of longitudinally disposed recesses cut in the face thereof, each of said recesses having a 80 portion of its bottom inclined upwardly toward the front end and the other portion curved upwardly, and having its rear end vertically at right angles to the inclined portion of the bottom; and means to impart a 85 slow forward movement and a quick return movement to said box and riffle boards.

In testimony whereof I have affixed my signature in presence of a witness.

ARTHUR E. CUSTER.

Witness:

SAM RANEY.
